(57) **CLAIM**

I claim the ornamental design for a pet toy, as shown and described.

DESCRIPTION

FIG. 1 is a perspective view of a pet toy showing my new design.

FIG. 2 is another perspective view thereof.

FIG. 3 is a front view thereof.

FIG. 4 is a back view thereof.

FIG. 5 is a left view thereof.

FIG. 6 is a right view thereof.

FIG. 7 is a top view thereof.

FIG. 8 is a bottom view thereof.

FIG. 9 is another perspective view thereof, showing the pet toy in a use state.

FIG. 10 is an enlarged view of portion 10 shown in FIG. 5; and,

FIG. 11 is an enlarged view of portion 11 shown in FIG. 9. The dashed broken lines depict portions of the pet toy that form no part of the claimed design, and the dot-dash broken lines define the bounds of enlarged views and form no part of the claimed design.

1 Claim, 11 Drawing Sheets
